FAN STAND

William W. Welch, Sr., Cincinnati, Ohio

Application November 27, 1948, Serial No. 149,851

Term of patent 14 years

(Cl. D26—7)

To all whom it may concern:

Be it known that I, William W. Welch, Sr., a citizen of the United States, residing at Cincinnati, in the county of Hamilton and State of Ohio, have invented a new, original, and ornamental Design for Fan Stand, of which the following is a specification, reference being had to the accompanying drawing, forming part thereof.

I claim:

The ornamental design for a fan stand, as shown.

WILLIAM W. WELCH, SR.
